Patented Oct. 20, 1914.

UNITED STATES PATENT OFFICE.

EDWARD O. GAY, OF RED SPRINGS, NORTH CAROLINA, ASSIGNOR OF ONE-THIRD TO WILLIAM JONES AND ONE-THIRD TO MARTIN MCKINNON, OF RED SPRINGS, NORTH CAROLINA; JNO. H. MCKAY ADMINISTRATOR OF SAID GAY, DECEASED.

FLOW.

1,113,982.

Specification of Letters Patent.

Patented Oct. 20, 1914.

Application filed October 3, 1913. Serial No. 793,166.

To all whom it may concern:

Be it known that I, EDWARD O. GAY, a citizen of the United States, residing at Red Springs, in the county of Robeson and State 5 of North Carolina, have invented certain new and useful Improvements in Plows, of which the following is a specification.

My present invention relates to improvements in that class of plows more especially 10 designed as cotton plows and in which the plow point is so mounted that it can be adjusted to the desired angle with respect to the line of draft and according to the condition of the soil to be turned and the particu- 15 lar work to be performed thereby.

Plows have heretofore been provided that have means for tilting the plow point to the angles desired relatively to the shoe or runner and such operation accomplished without 20 stopping the plow, and in many types of plows such adjustments of the plow point is effected by swinging lever and rack devices.

From practical experience with plows of the general type referred to, I have found 25 their structure and operation open to objections, partly for the reason that the construction is costly and particularly for the reason that in setting the plow point to the different angles, the relative positions of the 30 point, and the runner or shoe changes, and to such an extent that the point when set to dig a shallow furrow frequently rises above the plane of the riding face of the runner or shoe, or when set to dig a deep furrow it 35 projects so far below the said runner that a proper guiding or bearing of the plow is rendered difficult.

My present invention, which specifically 40 relates to improvements in the construction of plow shown in my Patent #992556 dated May 11, 1911, primarily has for its object to provide a plow of the character stated that can be cheaply made and in which the set 45 of the plow point is easily effected while running the plow and the setting of the said plow point either shallow or deep provided for without changing the relative positions of the plow point and the runner.

In my patented plow, I have found, from 50 practical experience that the means for shifting the plow point, by reason of the direct connection between the slidable block that carries the plow point and the slotted beam, under some conditions, becomes

clogged and subject to considerable friction, 55 which interferes with the quick and positive adjusting or shifting point desired in the use of plows of this kind.

My present invention has for its object to 60 positively overcome the objections noted and to provide such connections between the plow point and the shifting or standard lever that frictional contact of the parts and danger of their sticking, when clogged with dirt, is reduced to the minimum. 65

Another object of my invention is to provide for an easy and positive relative shifting of the plow beam and the plow point during the setting or shifting of the plow whereby to set the draft end of the beam, 70 high or low, to suit the adjusted angle or pitch of the plow point.

My present invention also embodies cer- 75 tain details of construction and peculiar combination of parts, all of which will be hereinafter fully explained, specifically pointed out in the appended claims and illustrated in the accompanying drawing, in which:

Figure 1 is a perspective view of my im- 80 proved plow, the point being adjusted to its most shallow position, and the beam at its lowest position. Fig. 2 is a side elevation thereof, the parts being in the position shown in Fig. 1, parts being shown in sec- 85 tion. Fig. 3 is a central vertical longitudinal section, the plow point being at its maximum vertical or digging position. Fig. 4 is a rear perspective view of parts of the plow. Fig. 5 is a perspective view of the plow 90 point carrier or sliding head, parts of the slotted lever standard and the link connec- 95 tion hereinafter referred to.

In my present construction of plow, the beam 1 has its front end formed with a draft hook 1^a and the rear end thereof is curved downwardly and pivotally connects with the rear end of the runner 2 to which is connected the removable shoe or riding member 20. 100

In my present construction of plow, the combined standard and lever 3 includes the upper or handle member 30, and the lower slotted standard portion 31, the opposite members of which straddle the front end of 105 the runner and are pivotally connected thereto by the bolt 4. The plow beam at that part within the sweep of the standard 3 is formed

with a rack segment 32 with which coacts the spring locking pawl 5 slidably mounted in the ears 50—50 that project rearwardly from the standard, as shown.

5 6 designates the plow point of any approved shape and the said point is removably held on a plow carrier or block 7, by the bolt 8, as is best shown in Figs. 3 and 5. The carrier 7 is slidably mounted within the 10 slotted end of the standard lever and the said carrier, like in my patent referred to is adapted for being reciprocably moved up and down within the said slotted standard, as the latter is swung backwardly and forwardly.

15 In my patent referred to the movement of the plow carrier is effected by joining the carrier with an eccentric slot in the beam. In practice, the slot in the standard frequently becomes clogged and the ground pressure on the plow is frequently such that the bolt sticks in the slot of the beam and renders the operation of the plow shifting means at times difficult and unreliable.

20 25 In my present form of plow, I have dispensed with the eccentric slot and cross bolt connection and in place thereof I connect the sliding plow carrying member to the beam by a compound lever connection, so arranged 30 that a powerful leverage is applied to the point carrying member when the lever is swung, sufficiently to positively overcome any tendency of the plow point carrier sticking in the slotted standard. The compound 35 lever connection referred to includes a bracket 80 fixedly secured to the curved end of the plow beam and projected inwardly therefrom and practically radially with respect to the pivotal connection of the stand- 40 ard.

A slotted link 9 is pivotally connected at one end 90 with the bracket 80 and at the other end 91, with the upper end of the point carrier, as is clearly shown in the drawing.

45 50 55 10 designates a second link connection that consists of two members 10^a and disposed in a plane substantially at right angles to the slotted link and projected vertically therefrom. Each of the link members 10 is pivotally connected, at the upper end, to a cross bolt 11 that passes through the upper end of the slotted standard and which carries a roller guide 12 that is held in engagement with the under edge of the plow beam.

60 65 16 The lower ends of the link members 80 are pivotally joined by a cross bolt 13 to the link member 9, while links 80 receive the links through the slot 15 and bolt 13 which carries a friction roller 14.

16 designates the plow handles and 17 the side braces therefor.

From the foregoing taken in connection with the drawing, the peculiar construction and the advantages of my present construction of parts will be readily apparent to

those skilled in the art to which my type of plow belongs.

In my present construction when the combined plow standard and lever is swung backwardly to give the plow its lowest inclination, for shallow digging, the slideable plow carrier is at its lower position, since the slotted link is now at a substantially horizontal position and moved backwardly to its limit, see Fig. 2. It will also be observed that when swinging the lever backwardly the link arms 10 are forced downwardly and at the same time the roller bearing that engages the lower edge of the beam lowers and hence the forward end of the beam drops to its limit, it being understood that when the lever standard is swung in the opposite or forward direction, the plow point will be forced down into the ground and the front end of the beam simultaneously raised (see full lines Fig. 3, dotted lines showing position when parts are as in Fig. 2) relatively to the degree in which the point is projected downwardly with respect to the runner.

90 It should be understood that the recess on the rear end of the runner 2 is of greater area than the lower end of the beam 1, so that the beam 1 may have a slight rocking movement on its pivotal connection with the runner 2, see Fig. 2 of the drawings. This is in order to enable the beam 1 and the runner 2 to have the necessary motion above described, the object of which is to enable the plow to be readily drawn through the ground and keep the plow point, when set to the position shown in Fig. 3, from tending to work up out of the ground, as would be the case were the beam 1, at its front end lowered below the normal line of draft.

105 What I claim is:

1. In a plow having a fixed runner, a beam whose rear end curves downwardly and pivotally joins with the rear end of the runner, a plow carrying standard pivotally mounted on the front end of the runner, and means for reciprocably moving the plow with respect to the standard, and simultaneously raising and lowering the plow beam as the said standard is swung in reverse directions.

110 115 120 125 2. In a plow point having a fixed runner, a standard pivotally connected to the front end of the runner, a plow beam pivotally connected to the rear end of the runner, a plow point carried by the standard, and means for maintaining a relatively fixed relation between the plow point, the beam and the runner as the plow is adjusted to its digging positions.

3. In a plow of the character stated, the combination with the beam having a downwardly curved rear end, a runner pivotally mounted on the said end and projected forwardly therefrom, a standard pivotally

mounted on the front end of the runner, a plow carried on the standard, and means operable through the backward and forward movements of the standard for effecting a 5 sliding movement of the plow on the standard and simultaneously raising and lowering the draft end of the plow beam.

4. In a plow, a plow carrying standard pivotally mounted to swing backwardly and 10 forwardly, and means for reciprocably moving the plow point with respect to the standard, the said means comprising a plow carrier slidable on the standard, a bracket projected inwardly from the rear end of the 15 beam, a slotted link slidable on the said bracket and pivotally connected to the plow carrier and a second link pivotally connected at one end to the slotted link, and pivotally connected at the upper end to the 20 standard.

5. In a plow having a fixed runner, a beam having a downwardly curved rear end pivotally connected to the rear end of the runner, a standard pivotally connected to

the front end of the runner, a plow point 25 carrier mounted to slide upon the standard, means for simultaneously moving the plow point on the standard and the beam relatively to the plow point when the said standard is moved backwardly or forwardly, the 30 said means consisting of a slotted link pivotally connected to the upper end of the plow carrier and slidably connected with the beam, a second link disposed at substantially right angles to the slotted link and 35 projected vertically therefrom, the said link being pivotally mounted on the slotted link and a pivotal connection that joins the said second link with the upper end of the standard, the said connection consisting of a cross 40 bolt on the standard that bears against the under edge of the beam as the parts are adjusted for use.

EDWARD O. GAY.
